LINK CHAIN FOR A BRACELET OR SIMILAR ARTICLE

Saul Ritter, New York, N. Y., assignor of one-half
to Marvin J. Bruner, New York, N. Y.

Application October 3, 1949, Serial No. 5,282

Term of patent 7 years

(Cl. D45—4)

To all whom it may concern:

Be it known that I, Saul Ritter, a citizen of the United States, residing at 101 Central Park West, New York city, New York, have invented a new, original, and ornamental Design for a Link Chain for a Bracelet or Similar Article, of which the following is a specification, reference being had to the accompanying drawing, forming part thereof.

Fig. 1 is a top plan view of a link chain for a bracelet or similar article embodying my new design;

Fig. 2 is a side elevation thereof;

Fig. 3 is a bottom plan view of the chain;

Fig. 4 is a top plan view illustrating the chain in an expanded position;

Fig. 5 is a perspective view of one of the top links of the chain.

I claim:

The ornamental design for a link chain for a bracelet or similar article, as shown and described.

SAUL RITTER.
